INDUSTRIAL TRUCK

Alexis de Sakhnoffsky, Grand Rapids, Mich., assignor to
The Yale & Towne Manufacturing Company, Stamford, Conn., a corporation of Connecticut

Application December 31, 1953, Serial No. 28,304

Term of patent 14 years

(Cl. D14—3)

Fig. 3.

Fig. 4.

To all whom it may concern:

Be it known that I, Alexis de Sakhnoffsky, a citizen of the United States and residing at Grand Rapids, State of Michigan, have invented a new, original, and ornamental Design for an Industrial Truck, of which the following is a specification, reference being had to the accompanying drawings, forming part thereof.

In the drawing,

Fig. 1 is a perspective view of an industrial truck embodying my new design;

Fig. 2 is another perspective view taken opposite Fig. 1;

Fig. 3 is an elevation in slight perspective of the left side thereof; and

Fig. 4 is a similar view of the right side thereof.

I claim:

The ornamental design for an industrial truck, substantially as shown.
